Primary Examiner — Susan Moon Lee

(74) Attorney, Agent, or Firm — Fredrikson & Byron, P.A.

(57) **CLAIM**

I claim the ornamental design for a module, as shown and described.

DESCRIPTION

FIG. 1 is a top view of my new design for a module;
FIG. 2 is a partial perspective view thereof;
FIG. 3 is a right side view thereof, the left side view being a
mirror image thereof; and,
FIG. 4 is a front view thereof, the rear view being a mirror
image thereof.
Outside of black, no claim is laid to color.

1 Claim, 4 Drawing Sheets(56)
